UNITED STATES PATENT OFFICE

1,924,552

MINING MACHINE

Morris P. Holmes, Claremont, N. H., assignor to
 Sullivan Machinery Company, a corporation of
 Massachusetts

Application October 12, 1931. Serial No. 568,306

16 Claims. (Cl. 262—28)

This invention relates to mining machines and more particularly has reference to improvements in cutter bar swinging mechanisms for such machines.

5 An object of this invention is to provide an improved cutter bar swinging mechanism for a coal mining machine. Another object is to provide an improved cutter bar swinging mechanism of the manually operable type. A further object is to provide an improved cutter bar swinging mechanism of the manually operable type whereby the cutter bar may be manually swung in either of opposite directions in an improved manner. These and other objects will, however, more fully appear.

In the accompanied drawing there is shown for purpose of illustration one form which the invention may assume in practice.

In this drawing:

20 Fig. 1 is a side elevational view of a coal mining machine having embodied therein the illustrative form of the improved cutter bar swinging mechanism.

Fig. 2 is a detail sectional view taken substantially on line 2—2 of Fig. 1.

Figs. 3 and 4 are detail sectional views taken substantially on lines 3—3 and 4—4 respectively, of Fig. 2.

In this illustrative construction the improved bar swinging mechanism generally designated 1 is shown embodied in a coal mining machine 2 of the flexibly fed, continuous cutter type although, it will be understood, that the same may be embodied in machines of various other types.

35 The coal mining machine shown herein is of the "strip or open pit" type and comprises a frame 3 mounted on a skid 4 for sliding movement over the surface of the material to be cut. The machine is fed by means of usual flexible feeding

40 means including a flexible feeding element 5 which engages a rotatable power driven feeding element 6 on the machine. Pivotaly mounted at 7 on the machine frame for swinging movement in a vertical plane relative thereto is a cutter bar 8 carrying on its margin for circulation thereabout a usual cutter bit cutter carrying chain 9.

Now referring to the improved bar swinging mechanism, it will be noted that secured to the hanger 10 of the cutter bar 8 is a bracket 11 having a flange 12 lying adjacent the circular cutter head 13 of the machine and forming bearing means cooperating with the circular head in the guiding of the cutter bar during its swinging movement. This bracket is herein composed of

two parts held together by bolts, and journaled within this bracket in bearing sleeves 14, 14 is a shaft 15 arranged with its axis perpendicular of the plane of the cutter bar as shown in Fig. 2. Formed integral with this shaft is an actuating element, herein a chain sprocket 16 which engages a flexible element, herein in the form of a chain 17. This chain functions as a rack and passes around the exterior periphery of the circular frame 13 and is attached at 18, 18 at its ends to the machine frame. Suitable means is employed for controlling rotation of the shaft 15 and in this instance comprises a ratchet wheel 19 keyed at 20 to the shaft 15. Engageable with the teeth of the ratchet wheel is a reversible pawl 21 pivotally mounted on a pin 22 fixed at 23 to the flange 12 of the bracket 11. This pawl is reversible and swingable into its different positions about the pin 22 and so held by a spring pressed plunger lock 24 mounted within a bore 25 formed in the pawl and engageable with a flattened surface 26 on the pin 22. The outer end of the shaft 15 is formed polygonal in cross section at 27 detachably to receive a suitable turning instrument for the shaft, herein a usual ratchet wrench or lever 28. As shown in Fig. 3, the bracket 11 is provided with a recess 29 to receive the ratchet wheel 19 and is provided with curved surfaces 30, 30 for guiding the chain 17 relative to the chain sprocket 16 in the manner shown in Fig. 4.

85 It will thus be seen that, as the operator grasps the ratchet lever 28 and swings the same back and forth, the shaft 15 is rotated, rotating therewith the sprocket 16 and causing the latter to travel along the chain rack 17, thereby moving therewith the cutter bar. The pawl 21 engaging the teeth of the ratchet wheel 19 at this time prevents reverse rotation of the shaft and as a result, the cutter bar is swung downwardly in its plane from the upper dotted line position shown in Fig. 1 to the full line position in that figure. The cutter bar may be swung in the opposite direction simply by shifting the pawl 21 into its reverse position and reversing the ratchet lever 28 on the shaft 15. The pawl 21 acts as a lock 90 and holds the cutter bar in the full line position shown in Fig. 1 during the cutting operation, and it is evident that the pawl may hold the bar in any desired position about its pivot.

95 As a result of this invention it will be noted that an improved bar swinging mechanism is provided for a coal mining machine whereby the cutter bar may be swung in an improved manner. It will further be noted that the improved cutter bar swinging mechanism is of a simple and 100 110

rugged design and may be manufactured at a minimum of expense and applied to a mining machine of a standard construction with a minimum of change. It will further be noted that, by 5 mounting the rotatable sprocket directly on the cutter bar and arranging its cooperating parts in the manner shown, an extremely powerful bar swinging force may be imparted to the cutter bar thereby enabling, with comparatively little 10 effort, manual swinging of the cutter bar about its pivot.

While there is in this application specifically 15 described one form which the invention may assume in practice, it will be understood that this form of the same is shown for purposes of illustration and that the invention may be modified and embodied in various other forms without departing from its spirit or the scope of the 20 appended claims.

What I claim as new and desire to secure by Letters Patent is:

1. In a mining machine, the combination with a frame and a kerf cutting cutter bar pivotally mounted thereon to swing in a vertical plane, said 25 frame having an arcuate guiding surface struck from the bar pivot axis, of mechanism for swinging said cutter bar about its pivot relative to said frame comprising a rack forming element loosely mounted on said arcuate guiding surface and attached at its ends to said frame, and a manually 30 rotatable actuating element disposed on a horizontal axis and carried by said cutter bar, said actuating element engaging said rack forming element and moving therealong during bar swing.

2. In a mining machine, the combination with a frame and a kerf cutting cutter bar pivotally mounted thereon to swing in a vertical direction, of mechanism for swinging said cutter bar about its pivot comprising a rotatable actuating element 40 disposed on a horizontal axis and carried by said bar and a cooperating flexible element attached to said frame.

3. In a mining machine, the combination with a frame and a kerf cutting cutter bar pivotally mounted to swing in a vertical direction, of mechanism for swinging said cutter bar about its pivot comprising a rotatable actuating element disposed on a horizontal axis and carried by said bar and a cooperating flexible element attached to said frame, and a ratchet and pawl device for preventing rotation of said actuating element in 50 one direction.

4. In a mining machine, the combination with a frame and a kerf cutting cutter bar pivotally mounted thereon to swing in a vertical direction, of mechanism for swinging said cutter bar about its pivot comprising a sprocket disposed on a horizontal axis and rotatably mounted on said cutter bar and a cooperating chain attached to said frame.

5. In a mining machine, the combination with a frame and a kerf cutting cutter bar pivotally mounted thereon to swing in a vertical direction, of mechanism for swinging said cutter bar about its pivot comprising a sprocket rotatably mounted on said cutter bar on a horizontal axis and a cooperating chain attached to said frame, and means on said cutter bar for guiding said chain relative to said sprocket.

6. In a mining machine, the combination with a frame and a kerf cutting cutter bar pivotally mounted thereon to swing in a vertical direction, said frame having an arcuate guiding surface struck from the bar pivot axis, of mechanism for swinging said cutter bar about its pivot including

a rotatable actuating element disposed on a horizontal axis and journaled on said bar, a cooperating rack forming element loosely mounted on said arcuate guiding surface and attached at its ends to said frame, said actuating element engaging said rack forming element and moving therealong during bar swing, and a lever for manually rotating said actuating element.

7. In a mining machine, the combination with a frame and a kerf cutting cutter bar pivotally mounted thereon to swing in a vertical direction, of mechanism for swinging said cutter bar about its pivot including a sprocket, a horizontal shaft journaled on said bar and to which said sprocket is secured, a chain cooperating with said sprocket and attached to said frame, and means for rotating said shaft.

8. In a mining machine, the combination with a frame and a kerf cutting cutter bar pivotally mounted thereon to swing in a vertical direction, of mechanism for swinging said cutter bar about its pivot including a sprocket, a horizontal shaft journaled on said bar and to which said sprocket is secured, a chain cooperating with said sprocket and attached to said frame, means for rotating said shaft, and ratchet and pawl mechanism for preventing rotation of said shaft in a direction opposite from that in which said shaft is rotated.

9. In a mining machine, the combination with a frame and a kerf cutting cutter bar pivotally mounted thereon to swing in a vertical direction, said frame having an arcuate guiding surface struck from the bar pivot axis, of manually operable mechanism for swinging said cutter bar about its pivot including a rotatable actuating element 105 journaled on said bar on a horizontal axis parallel with the bar pivot axis, and cooperating reaction element loosely mounted on said arcuate guiding surface and attached at its ends to said frame, said actuating element engaging said reaction element and moving therealong during bar swing.

10. In a mining machine, the combination with a machine frame and a cutter bar pivotally mounted thereon, of mechanism for swinging and guiding said cutter bar including a lateral boss 120 rigidly fixed to said bar and cooperating with an arcuate guide flange on the machine frame, a sprocket housed within said boss and a chain passing about said arcuate guide flange and engaging said sprocket, said sprocket being rotatable 125 to effect travel thereof along said chain thereby to swing the cutter bar.

11. In a mining machine, the combination with a machine frame and a cutter bar pivotally mounted thereon, of mechanism for swinging and guiding said cutter bar including a lateral boss rigidly fixed to said bar and cooperating with an arcuate guide flange on the machine frame, a sprocket housed within said boss, and a chain 130 passing about said arcuate guide flange and engaging said sprocket, said sprocket being rotatable to effect travel thereof along said chain thereby to swing the cutter bar, said boss having guiding surfaces with which said chain engages to guide the latter relative to said sprocket.

12. In a mining machine, the combination with a machine frame and a cutter bar pivotally mounted thereon, of mechanism for swinging and guiding said bar including a boss rigidly fixed to said bar and cooperating with an arcuate guide 145 flange on the machine frame, said boss having spaced parallel walls having formed therebetween a chamber, a horizontal shaft journaled within said spaced walls and extending through said chamber, a sprocket fixed to said shaft, a flexible 150

- chain passing about the arcuate guide flange on said frame and fixed at its ends to said frame, said chain passing through said chamber in engagement with said sprocket, and means for rotating said shaft to effect travel of said sprocket along said chain to swing said cutter bar and for locking said shaft in its adjusted position. 5
13. In a mining machine the combination with a machine frame and a kerf cutter pivotally mounted thereon, of mechanism for swinging and guiding said kerf cutter including bearing means formed on said kerf cutter and cooperating with an arcuate guide on the machine frame, a sprocket journaled within said bearing means, and a chain passing around said arcuate guide and attached at its ends to said frame, said sprocket engaging said chain and rotatable to effect travel thereof along said chain thereby to swing the kerf cutter. 10
14. In a mining machine, the combination with a machine frame and a kerf cutter pivotally mounted thereon, of mechanism for swinging and guiding said kerf cutter including bearing means formed on said kerf cutter and cooperating with an arcuate guide on the machine frame, a sprocket journaled within said bearing means, and a chain passing around said arcuate guide and attached at its ends to said frame, said sprocket engaging said chain and rotatable to effect travel thereof along said chain thereby to swing the kerf cutter. 15
15. In a mining machine, the combination with a machine frame and a kerf cutter pivotally mounted thereon, of mechanism for swinging and guiding said kerf cutter including a bearing means formed on said kerf cutter and cooperating with an arcuate guide on the machine frame, a horizontal shaft journaled within said bearing means, a sprocket fixed to said shaft, a flexible chain passing around the arcuate guide on said frame and fixed at its ends to said frame, said sprocket engaging said chain, and means for rotating said shaft to effect travel of said sprocket along said chain to swing the kerf cutter and for locking said shaft to hold said kerf cutter in its adjusted position. 20
16. In a mining machine, the combination with a machine frame and a kerf cutter pivotally mounted thereon, of mechanism for swinging said kerf cutter relative to said frame including bearing means rigidly fixed to said kerf cutter, a rotatable actuating element journaled within said bearing means, an arcuate rack element on said frame, said actuating element engaging said rack element and rotatable to effect travel thereof along said rack element thereby to swing the kerf cutter, and means associated with said actuating element for holding the latter against rotation to lock the kerf cutter in its adjusted position. 25
